UNITED STATES PATENT OFFICE.

GEORGE S. LEWIS, OF SPRINGFIELD, AND EARL B. SMITH, OF CHICOPEE FALLS,
MASSACHUSETTS.

GUN.

Application filed April 1, 1925. Serial No. 19,837.

To all whom it may concern:

Be it known that we, GEORGE S. LEWIS, a resident of Springfield, in the county of Hampden and State of Massachusetts and EARL B. SMITH, a resident of Chicopee Falls, in said county and State, both citizens of the United States of America, have jointly invented a new and useful Gun, of which the following is a specification.

10 Our invention relates to improvements in guns, and more particularly to the type of guns commonly known as rifles, and consists essentially, of a stock and a barrel of any approved and suitable type, a slotted frame 15 receivable in said stock and adapted to have said barrel attached thereto, and being equipped with a trigger having a sear, a latch-provided breech-block mounted on said frame with a cut-out plate between, and attached to said frame by means of screws 20 passing through the slots therein, a spring-pressed firing-pin bolt in said breech-block, and an ejector in said frame and operated by or in connection with said breech-block, 25 which latter with said plate is adapted to be moved longitudinally on the frame, together with such other parts and members as may be necessary and desirable in order to render the gun or rifle complete and serv- 30 iceable in every respect, all as hereinafter set forth.

The primary object of our invention is to produce a gun which, while simple in construction and operation, and inexpensive to 35 manufacture, is strong, safe, and efficient, and consists of parts that are practically the fewest possible, can be easily and quickly assembled, and are not liable to get out of order or become broken or damaged.

40 Further objects are to provide a gun with a structurally simple frame, and to provide means therein to prevent the firing-pin from coming into contact with the cartridge at the time the breech-block is completely 45 closed on a cartridge during the loading operation.

The barrel of this gun or rifle can be easily and quickly detached from the stock and frame, and as easily and quickly attached thereto, and the operation of detaching said barrel from said stock releases said frame from said stock.

50 Other objects and advantages will appear in the course of the following description.

55 We attain the objects and secure the ad-

vantages of our invention by the means illustrated in the accompanying drawings, in which—

Figure 1 is a side elevation of a rifle which embodies a practical form of our invention; Fig. 2, a longitudinal, vertical section through said rifle, taken on lines 2—2, looking in the direction of the associated arrow, in Fig. 3; Fig. 3, an enlarged bottom plan of the frame and attached parts 60 of said rifle; Fig. 4, an enlarged top plan of said frame and certain of the parts attached thereto and carried thereby; Fig. 5, an enlarged, longitudinal, vertical section 65 through said frame and parts, on lines 5—5, looking in the direction of the associated arrow, Fig. 4; Fig. 6, an enlarged bottom plan of the breech-block and firing-pin bolt; Fig. 7, an enlarged cross section through 70 said breech-block and bolt, on lines 7—7, looking in the direction of the associated arrow, Fig. 6; Fig. 8, an enlarged, longitudinal, vertical section through said breech-block, showing portions of said bolt in elevation; Fig. 9, an enlarged side elevation 75 of one of the breech-block screws; Fig. 10, an enlarged top plan of the cut-out plate.

Similar reference characters designate similar parts throughout the several views.

In the first two views adjacent end portions of the stock and barrel of a rifle are represented at 1 and 3, respectively, and in Fig. 3 appears the breech portion of said barrel. The stock 1 has an integral forestock, is equipped with the usual trigger guard 4, and hollowed out longitudinally in the top portion to receive what is termed a frame 6, and the breech portion of the barrel 3. The barrel 3 is secured to the frame 6 adjacent to the forward terminal thereof by 80 means of a screw 8, and said frame at such terminal is secured to the stock 1 by means of a screw 9. The frame 6 is equipped at the rear terminal with a trigger 10 which extends downwardly through a slot 11 in the stock 1. Extending forwardly from the slot 11 in the stock 1 is a slot 12, and in front of said last-named slot is a slot 13. The stock is recessed to accommodate the head of the screw 8, and has a passage 14 therethrough for the screw 9. An annulus 15 is fixed in the bottom of the passage 14, and prevents the screw 9 from being entirely removed from the stock 1, due to the fact 100 that the screw-threaded upper portion of 105 110

said screw is larger than the lower portion thereof, and too large to pass through the opening in said annulus. On the bottom of the barrel 3 is a lug 16 which is received in a slot 17 located in the frame 6 back of a screw-threaded opening 18 in said frame for the screw 9. The screw 8 is passed upwardly through the slot 17 into a tapped opening in the lug 16.

10 It will now be seen that the frame 6 and the barrel 3 are securely held together by means of the lug 16 and the screw 8, and that both said frame and barrel are securely held in the groove in the stock 1 by means 15 of the screw 9, the sides of said groove holding the frame and barrel against lateral displacement.

The trigger 10 at the upper end has an integral sear 19 which is received and operates in a slot 20 in the frame 6 adjacent to the rear end thereof. The trigger 10 at the upper end back of the sear 19 is mounted on a pivot pin 21 which extends through the sides of the frame 6 and across the slot 20. In front of and a little above the horizontal plane of the pivot 21 is a stop pin 22, which also passes through the sides of the frame 6 and across the slot 20. The pin 22 is in position to limit the upward movement of the sear 19 and the forward movement of the trigger 10. The back part of the trigger 10 projects beneath and beyond the rear end of the slot 20, and a spring 23 is pocketed in such projecting part and arranged to bear against the under side of the frame 6 at a point back of said slot. Normally the spring 23 retains the trigger 10 in its forward position with the sear 19 in contact with the pin 22 or with parts 40 above the upwardly projecting hook of said sear.

The frame 6 consists of a bar having therein, in addition to the tapped opening 18 and the slots 17 and 20, the two former being in the longitudinal center and the latter adjacent to one longitudinal side of said bar, two slots 24 which are located adjacent to the other side of said bar, a notch 25 between said last-named slots and opening through said last-named side of the bar, and a groove 26 in the longitudinal center of the bar. The forward slot 24 opens at the top into the bottom of the groove 26, and the slot 17 also opens into said groove at the forward end of the same. An extractor 27 is slidably arranged in the groove 26, said extractor having on top a notched projection or lug 28 of ordinary construction to receive the shell of the cartridge and engage the rim of said shell. In the extractor 27 behind the lug 28 is a recess 29 the inner longitudinal edge of which is in line with the inner longitudinal edge of the forward slot 24. The recess 29 opens through the longitudinal edge of the extractor 27 which is

adjacent to the outer longitudinal edge of the forward slot 24. The under sides of the edges of the slots 24 at their forward ends are countersunk, as represented at 30—30, to receive the heads of two screws 70 31. These screws are adapted to fit and slide in the slots 24, and each of the heads of said screws is cut away on opposite sides to form a key 32 that is also adapted to be received in either of said slots. 75

The breech of the barrel 3 is recessed in the customary manner and as illustrated in Fig. 2, to receive and accommodate the forward terminal portion and the lug 28 of the ejector 27. 80

Mounted on the frame 6 is a thin, cut-out plate 33 that has therein two holes 34 to receive the screws 31, and a notch 35 which is in position to align with the notch 25. 85

Mounted on the plate 33 is a breech-block 36, and this breech-block has therein two tapped openings 37 extending from the bottom upwardly. The openings 37 are in position and adapted to receive the screws 31. The screws 31 are passed from below through the frame slots 24 and the plate openings 34, and screwed up into the openings 37, to hold said plate and said breech-block on said frame. When the screws 31 are first inserted, the breech-block 36 is moved forward until the openings 37 are directly over the forward ends of the slots 24, which enables the screw keys 32 to enter the countersunk recesses 30, as said screws are turned up into said openings. The screws 31 are not turned up far enough unduly to bind the parts, and are left so that the keys 32 can enter the slots 34 back of the recesses 30. The forward screw 33 passes through the recess 29 in the extractor 27. The slots 24 and the recess 29 are of sufficient length to permit the breech-block 26, with the plate 33, and the extractor 27 to be moved longitudinally to the extent required, and as will hereinafter be explained. 100 Although the recess 29 is shorter than the slot 24 below, said recess is of sufficient length to permit the front screw 31 to move some little distance in either direction without moving the extractor 27. 105

In the side of the breech-block 36 which is adjacent to the notches 25 and 35, is a notch 38 that opens through the bottom of said breech-block to receive a latch 39. The latch 39 is pivotally connected at 40 with the breech-block 36. The pivot 40, after being passed laterally through the inner terminal portion of the latch 39, is dropped into a slot 41 milled in the underside of the breech-block in position properly to locate said pivot, and two filling blocks 42 are forced into said slot on opposite sides of said latch and below said pivot to retain the same in place. The latch 39 is thus arranged to enter the slots 35 and 25, when 110 115 120 125 130

the breech-block, with the plate 33, is located with the slot 38 in alignment with said first-named slots, and said latch is turned down on the pivot 40, and to lock said 5 breech-block and prevent the same from being moved longitudinally in either direction.

Slidingly arranged in a longitudinal slot 43, of suitable size and shape in the breech-block 36, is a bolt 44 which is provided at its forward end with an integral firing-pin 45. The slot 43 opens through both ends and the bottom of the breech-block, and is adjacent to the side thereof which is opposite 15 to that in which is located the latch notch 38. The front end of the breech-block is recessed in the usual manner, above the rear end of the firing-pin 45, as shown at 46, to receive the rim of the cartridge shell. At 20 the rear end of the bolt 44 is a handle or knob 47, and in the under side of said bolt, over the sear 19, are two notches 48. The front notch 48 is the arresting notch, and the rear notch 48 is the cocking notch. Normally 25 the cocking notch 48 is covered by the plate 33 below, so that the sear hook can not enter said notch. The bolt 44 intermediate of its ends is cut down from above to form front and rear lugs or shoulders 49 and 50, respectively, and space between for a spring 52. A pin 51 is inserted in the breech-block and passes through the sides thereof and the slot 43 therein, in front of the shoulder 50, and the latter is normally 30 retained in engagement with said pin by means of the spring 52 which is located in the slot 43 between said pin and the shoulder 49.

The parts and members of this rifle are 35 assembled in the following manner:

The spring 52 is inserted in the slot 43, the shoulder 49 is over the front end of said spring, and the bolt 44 is drawn rearwardly and said spring compressed between 40 said shoulder and the pin 51 until said bolt can be pressed into said slot, wherein it occupies the position best shown in Figs. 6 and 8. The extractor 27 is placed in the groove 26, the plate 33 is placed on the frame 6 with the openings 34 over the openings 37, the breech-block 36 is placed on said plate, and the screws 31 are inserted and arranged in the manner previously described. The barrel 3 is attached to the 45 frame 6 by means of the screw 8, and the trigger 10 is inserted in the opening 11 while at the same time said frame and barrel are placed in the grooved top of the stock 1. And lastly the frame and barrel are secured to the stock by means of the screw 9.

To remove the barrel and frame from the stock, it is simply necessary to turn the screw 9 downwardly out of engagement with said frame, and lift the parts from the 50 stock. Upon removing the screw 8 the frame

and barrel can be detached. If it be desired to remove the breech-block from the frame, the breech-block is moved forward, after the barrel has been detached, until the screws 31 are in the forward ends of the slots 24, 55 and said screws are taken out. When the breech-block is detached, the bolt 44 and the spring 52 can be removed therefrom without difficulty.

When the parts are assembled, the barrel 75 prevents the breech-block from being moved forward far enough to carry the heads of the screws 31 into the recess 30, consequently the keys 32 are always in the slots 34, and thereby said screws are prevented from 80 turning and becoming loose.

The loading operation is described as follows:

The latch 39 is thrown up, and the breech-block 36 is drawn back, by means 85 of the knob 47, and through the medium of the bolt 44 and the spring 52—see dotted-line positions in Fig. 1. When the breech-block moves rearwardly, said breech-block carries with it the cut-out plate 33, through 90 the medium of the screws 31. At this time the plate 33 contacts with the hook of the sear 39, which hook normally projects above the top of the frame 6 into the path of said plate and in position to enter the notches 95 48, and rocks said sear on the pivot 21 rearwardly and carries the trigger 10 rearwardly, against the resiliency of the spring 23. Also, at this time, the forward screw 31 actuates the ejector 27 rearwardly far 100 enough to position the lug 28 about midway between the breech-block and the barrel 3. The cartridge (not shown) is now introduced into the space between the breech-block and barrel, and placed in the notch 105 in the lug 28, with the rim of said cartridge behind said lug. Next, the breech-block is moved forwardly to advance the extractor and the cartridge, and push the latter into the barrel. In moving forward with the 110 breech-block the plate 33 clears the sear 19, and the spring 23 rocks said sear upwardly into the path of the rear or arresting notch 48, but the front or cocking notch 48 remains covered by said plate, so that said sear can 115 not enter the same. The parts are now in the positions shown in Fig. 2, and the bolt 44 is held against forward movement by the sear in engagement with the arresting notch 48 at the rear end of the same.

The loading operation is finally completed by forcing the breech-block forward against the breech of the barrel, and into the position shown by full lines in Fig. 1, and thus moving the cartridge as far forward as it 120 will go, with the extractor lug 28 in the recesses provided for the same in the breech of the barrel, and the rim of the cartridge in the recess 46 in the front end of the breech-block, and throwing the latch 39 down into 125 130

the notches 35 and 25 in the plate 33 and frame 6. During this final movement of the breech-block the sear 19 holds back the bolt 44, and it is necessary to exert sufficient force 5 on said breech-block to overcome the resistance of the spring 52, which is compressed by the pin 51 as said pin moves with the breech-block away from the shoulder 50. Since the breech-block moves rearwardly 10 while the bolt 44 remains stationary, the forward end of said breech-block passes beyond the corresponding end of the firing-pin 45, and the latter is prevented from contacting with the cartridge at the time the latter 15 is finally seated ready to be fired. Thus all danger of premature discharge is prevented. To fire the rifle which has been loaded in the manner described above, grasp the knob 47 and draw back the bolt 44, against the 20 siliency of the spring 52, until the sear 19 snaps into the front or cocking notch 48, and pull the trigger 10. When the trigger 10 is pulled, the sear 19 is withdrawn from the cocking notch 48 and the bolt 44 is thus 25 released to the spring 52, which latter immediately acts to drive forward with great force said bolt, and to project the firing-pin against the rim of the cartridge, thus causing the latter to explode.

30 The empty cartridge shell is withdrawn from the barrel 3 when the breech-block 36 is next retracted, since the extractor 27 is carried rearwardly with said breech-block. The lug 28 either withdraws the empty shell 35 entirely from the barrel, or else to an extent sufficient to enable the shell to be thrown out, depending, of course, on the length of the shell.

40 More or less change in the shape, size, construction, and arrangement of some or all of the parts of this gun may be made, without departing from the spirit of our invention or exceeding the scope of what is claimed.

45 What we claim as our invention, and desire to secure by Letters Patent, is—

1. In a gun, a frame equipped with a sear, a breech-block slidably mounted on said frame, and a spring-pressed firing-pin bolt in said breech-block, said bolt having therein arresting and cocking notches, and said breech-block being provided with a member which closes the entrance to said cocking notch except when said bolt is drawn back into firing position.
2. In a gun, a frame equipped with a sear, a breech-block slidably mounted on said frame, a plate between said frame and breech-block and attached to the latter, and a spring-pressed firing-pin bolt in said breech-block, said bolt having therein arresting and cocking notches, and said plate being adapted to cover said cocking notch except when said bolt is drawn back into firing position.

3. In a gun, a frame, a spring-pressed trigger pivotally connected with said frame, and provided with a sear, a breech-block slidably arranged on said frame, a spring-pressed firing-pin bolt in said breech-block, 70 said bolt having notches to receive said sear, and said breech-block being provided with a member which normally closes the entrance to one of said notches.

4. In a gun, a frame, a spring-pressed trigger pivotally connected with said frame, and provided with a sear, a non-rotating non-tilting breech-block slidably arranged on said frame, a spring-pressed firing-pin bolt in said breech-block, said bolt having 80 notches to receive said sear, and said breech-block being provided with a member into the path of which said sear projects.

5. In a gun, a frame, a spring-pressed trigger pivotally connected with said frame, and provided with a sear, a breech-block slidably arranged on said frame, a spring-pressed firing-pin bolt in said breech-block, said bolt having notches to receive said sear, and said breech-block being provided with 90 a member which normally closes the entrance to one of said notches, and into the paths of which said sear projects.

6. In a gun, a frame, a cut-out plate mounted on said frame, a breech-block mounted on said plate, means to attach said breech-block and plate to said frame and permit them to slide together thereon, a spring-pressed firing-pin bolt in said breech-block, said bolt having notches therein, and a trigger pivotally connected with said frame and provided with a sear which is in the path of said plate and adapted to enter the notches in said bolt.

7. In a gun, a frame having slots therein 105 which are countersunk at their forward ends, a breech-block and a perforated cut-out plate mounted on said frame, a spring-pressed firing-pin bolt having notches there- in in said breech-block, screws adapted to be 110 passed through said slots and the perforations in said plate into threaded engagement with said breech-block, said screws having keys to fit said slots, and the heads of said screws being receivable in the countersunk 115 portions of said frame, and a trigger pivotally connected with said frame and provided with a sear which is in the path of said plate, and adapted to enter said notches when released by said plate, or moved into uncov- 120 ered position.

8. The combination, in a gun, with a barrel, of a frame, means to attach said barrel to said frame, the latter having slots therein which are countersunk at their forward 125 ends, a breech-block and a perforated cut-out plate mounted on said frame, a spring-pressed firing-pin bolt having notches there- in in said breech-block, screws adapted to be 130 passed through said slots and the perfora-

tions in said plate into threaded engagement with said breech-block, said screws having keys to fit said slots, and the heads of said screws being receivable in the countersunk portions of said frame, and a trigger pivotally connected with said frame and provided with a sear which is in the path of said plate, and adapted to enter said notches when released by said plate or moved into position, the construction and arrangement of parts being such that, when said barrel is attached to said frame, said barrel prevents said breech-block from being moved forwardly far enough to carry the heads of said screws into said countersunk portions.

9. In a gun, a frame having a slot therein, a trigger provided at the top with a sear which is located in said slot, a pivot pin in said frame and passing through the rear-end portion of said sear, a stop pin in said frame and extending across said slot above said sear at a point intermediate of the ends thereof, and a spring arranged normally to retain said sear in engagement with said stop pin.

10. In a gun, a grooved and slotted frame, an extractor slidably arranged in the frame groove, and having a recess therein over one of the frame slots, a breech-block arranged on said frame over the recessed part of said extractor, and screws passing through said slots into threaded engagement with said breech-block, one of said screws passing through said extractor recess, whereby said extractor is actuated backward and forward with said breech-block.

11. In a gun, a notched frame, a breech-block slidably arranged on said frame, and provided with a latch adapted to enter the notch in said frame when said breech-block is in its most advanced position, a notched spring-pressed firing-pin bolt in said breech-block, a spring-pressed trigger having a sear and pivotally connected with said frame, said sear being adapted to enter the notches in said bolt, and means to prevent said sear from entering one of said notches when said breech-block is advanced, but to release said sear and permit it to enter one of said notches as said breech-block approaches the forward end of its travel, said bolt then being held by said sear when said breech-block is forced forwardly to the full extent and far enough to enable said latch to enter said notch.

12. In a gun, a notched frame, a breech-block slidably arranged on said frame, and provided with a latch adapted to enter the notch in said frame when said breech-block is in its most advanced position, a notched spring-pressed firing-pin bolt in said breech-block, a spring-pressed trigger having a sear and pivotally connected with said frame, said sear being adapted to enter the notches in said bolt, and a plate, between said frame

and breech block and moving with the latter, to prevent said sear from entering one of said notches when said breech-block is advanced, but to release said sear and permit it to enter one of said notches as said breech-block approaches the forward end of its travel, said bolt then being held by said sear when said breech-block is forced forwardly to the full extent and far enough to enable said latch to enter said notch.

13. In a gun, a frame, a non-rotating non-tilting breech-block slidably arranged on said frame, a spring-pressed firing-pin bolt in said breech-block, and means to hold said bolt against the force of its spring when said breech-block, after being moved with said bolt freely forward, is actuated now against the force of said spring into closed position.

14. In a gun, a frame, a non-rotating non-tilting breech-block slidably arranged on said frame, a spring-pressed firing-pin bolt in said breech-block, means to hold said bolt against the force of its spring when said breech-block, after being moved with said bolt freely forward, is actuated now against the force of said spring into closed position, and means subsequently to hold said bolt after being drawn rearwardly against the force of said spring into cocked position.

15. In a gun, a frame provided with a spring-pressed trigger having a sear, a breech-block slidably arranged on said frame, a spring-pressed firing-pin bolt in said breech-block, said bolt having arresting and cocking notches therein into which said sear is adapted to enter, and said breech-block being provided with a member which is adapted to close said cocking notch to the entrance of said sear, except while said breech-block is in its most advanced position and said bolt is drawn rearwardly into firing position.

16. In a gun, a breech-block having longitudinal and transverse intersecting slots therein, a latch laterally arranged relative to said breech-block, and provided with a pivot pin arranged in said transverse slot with said pin in said longitudinal slot, and filling blocks in said longitudinal slot on both sides of said latch to hold said pin in place.

17. In a gun, a breech-block having a slot therein which opens through the end and bottom thereof, a pin extending through the sides of said breech-block and across said slot, a firing-pin bolt in said slot, said bolt being recessed in its upper edge to provide shoulders one of which is adapted to bear against said pin when said firing-pin is in discharged position, and a spring in said breech-block between said pin and the other of said shoulders and always in contact therewith.

18. In a gun, a slotted, grooved, and recessed frame, a spring-pressed trigger hav-

ing a sear pivotally connected with said frame in one of the slots therein, a recessed extractor slidably arranged in the groove in said frame, a perforated and recessed plate mounted on said frame over a portion of said extractor, a breech-block mounted on said plate, screws passing through others of the frame slots and through the plate perforations into threaded engagement with 10 said breech-block, and one of said screws passing through the extractor recess, a latch pivotally connected with said breech-block, and adapted to enter the recesses in said plate and frame, when said breech-block 15 with said plate is in its most advanced position, and a spring-pressed firing-pin bolt in said breech-block, said bolt having notches therein, the construction and arrangement of parts being such that, when said plate 20 is moved rearwardly with said breech-block, the plate forces said sear downwardly, and, when said plate is moved forwardly

with said breech-block, the plate releases said sear and permits the same to enter the rear bolt notch, and thereby hold said bolt while said breech-block is moved into its most advanced position, the bolt then being adapted to be drawn back to enable the sear to enter the forward notch therein.

19. In a gun, a frame having a slot therein which is countersunk at its forward end, a non-rotating breech-block mounted on said frame, a spring-pressed firing-pin bolt in said breech-block, a screw adapted to pass through said slot into threaded engagement 30 with said breech-block, said screw having a key to fit said slot, and the head of said screw being receivable in the countersunk portion of said frame, and a trigger pivotally connected with said frame and provided 35 with a sear to engage said bolt.

GEORGE S. LEWIS.
EARL B. SMITH.
